UNITED STATES PATENT OFFICE

CLYDE DEAN, OF CHICAGO, ILLINOIS

PRINTING PRESS

Application filed August 1, 1928. Serial No. 296,656.

My invention in general relates to printing presses and more particularly to improved means and methods for multi-water color printing.

- 5 The object of the invention is to provide a device of the kind described whereby multi-water color printing is achieved while overcoming the disadvantages heretofore inherent in mechanisms of this nature.
- 10 Another object is to provide an independently operated adjustable device adapted to be detachably connected to standard printing presses which are thereby equipped to print in water colors, if desired, with a great
- 15 saving of time and labor.

As is well known, printing with oil colors presents no difficulties in the art, due to the fact that by reason of their comparatively slow drying properties these oil colors can 20 be applied at leisure, there being no necessity for haste in the various processes of printing. However when printing with water colors, which dry rapidly, it is essential that the elements coating with the printing rollers be 25 kept moistened with the colors sufficiently long to correctly carry out their appropriate functions. Quick action, therefore, in view of the rapid drying of the water colors alluded to is necessary, this being achieved 30 by the hereinafter described method and mechanism whereby the impressing of the colors is expeditiously accomplished. Up to the present time printing with water colors has been accomplished only at the expense of 35 considerable time and labor, the time alone running into periods in excess of a week. By the device herein described and illustrated, I am enabled to effect a great saving of time and labor in making water color prints, the

40 means and methods for accomplishing the objects pointed out now being described in the hereinafter specification, reference being had to the accompanying drawings in which,

45 Figure 1 is an elevational view of my invention as applied to a conventional printing press.

Figure 2 is a top plan view of one of the roller adjusting means of my novel attachment.

50 Figure 3 is a plan view thereof.

Figure 4 is a front elevational view of the device, and

Figure 5 is an enlarged side elevational view of my novel attachment, parts of the attached printing press being broken away. 55

With more particular reference to the drawings wherein similar characters of reference indicate corresponding parts of the preferred form of my invention, 9 designates the frame of a conventional printing press, 60 secured to a base 10. Pivots mounted on the frame is the shaft 11, secured to the power operated wheel 12, having a crank portion 13, to which is secured an arm 14, connected at its other end to the rockingly mounted bed 15 65 supporting the platen 16. Also secured to the shaft 11 are a pair of arms 19 and 20 to the ends of which are resiliently secured by springs 21, the supporting rollers 22, these latter being adapted to ride over the tracks 70 23. The rollers 22 form the supporting means for the inking rollers 25, 26. The above recited details form no part of my invention, being conventional to the art. The foregoing description, however will serve to more 75 clearly set forth the manner in which my invention, now to be described, is attached to the frame of the ordinary printing press.

My invention comprises a pair of slotted depending arms 27, 28, which are attached 80 to the sides of the frame 9 by screw bolts 29, 30, passed through corresponding slots 29', 30', in the side walls of the frame 9, the slotted arms serving as an adjustable supporting means for the fountain 31. In the 85 fountain 31 are mounted a plurality of rollers 32, 33, and 34, roller 34 being supported directly in the walls of the fountain, while rollers 32 and 33 are journaled in bearings 35, 36. The bearing 36 has been designed and constructed with a view to providing a means of elevating and lowering the roller 32 relatively to the fountain and to the coating roller 33, which latter is not susceptible of 90 translational movement. As best shown in Figures 2 and 5, the bearing 36 comprises a U-shaped member 62 with a pair of flanges 63, having slots 64. Slidably confined within the U-shaped member is a shoe 65, resiliently supported by a spring 66, the shoe being sus- 100

ceptible of adjustment by means of a screw bolt 67, threaded in a strap 68, bolted to the U-shaped member. It will be obvious that the U-shaped member may be adjusted horizontally by means of the slots 64 wherein ride the bolts 69. When the bolt 67 is turned, the shoe 65 and consequently the shaft 50 supporting the roller 32 may be elevated or lowered. With a view to providing horizontal adjustment in addition to vertical adjustment for the fountain, side straps 37, 38, integral with the arms 27, 28 and having slots 37', 38', respectively are provided, attachment being made to the fountain by the screw bolts 39, 40.

As shown in Figures 1 and 5 it will be observed that the roller 33 which supplies the water color to the inking rollers 25, 26, is engaged by a scraper 41 which serves to remove excess ink from the roller 33. This scraper is preferably secured adjustably to the front wall of the fountain by means of the screw bolt 42. The manner in which the water color is spread over the inking rollers is as follows: On their downward reciprocation the entire surface of the inking rollers 25, 26 will be evenly moistened by the action of the cooperating distributing plate 17. The supporting rollers 22 in the usual manner travel over the tracks 23, this causing the inking rollers 25, 26 to engage the roller 33 of the fountain. After the upward reciprocation of the inking rollers, the paper, lithograph, etc. on the platen will engage the moistened printing surface 18 of the printing press. It will be observed that the fountain and the rollers therein are actuated from a source of mechanical energy independent of the printing press actuating means. In the present case this independent source of mechanical energy consists in the provision of an electric motor 43 on the shaft of which is mounted a plurality of pulleys 57, 58, 59, these pulleys being selectively engaged by a belt 60 engaging a similar plurality of pulleys on a shaft 61 having a worm 44 meshing with a worm wheel 45. The worm wheel 45 is coupled to the same shaft 46 on which is secured a sprocket 47 connected by a chain 48 to another sprocket 49 secured to the shaft 50 of the roller 32, it being apparent that when the motor is energized, the sprockets 47 and 49 and consequently the roller 32 will be mechanically actuated through the elements described. As shown in Figures 4 and 5, the rollers 32, 33 and 34 are operatively connected by the interengaging gears 51, 52 and 53, it being apparent that the water color ink in the fountain will be conveyed by these mutually engaging rollers to the inking rollers 25, 26. Means are also provided to adjust the distributing plate 17, this consisting in the provision of grooves 54 formed in the arms 27, 28. A downwardly projecting part 55 of the bracket 55 is clamped in the walls of

the grooves 54 by a set screw 56. When desired, the plate 17 may be raised or lowered by loosening this set screw 56. When the plate is in the desired position, the screw will be again tightened.

As pointed out above, the chief difficulty in printing with water colors has been their comparatively quick drying properties, this necessitating special means and apparatus, the entire process requiring a considerable period of time. As is well known water colors are generally recognized as superior for artistic purposes by reason of their vivid, natural portrayal of the subjects desired to be conveyed through the medium of the printing press. It will be noted that in the present invention, a separate source of mechanical energy is employed to actuate the mechanism of my water color fountain which latter may be applied to any of the conventional types of printing presses now on the market by means of the slotted arms 27, 28 in the manner indicated. When not otherwise formed, it will only be necessary to provide holes in any appropriate part of the frame of the cooperating printing press to accommodate my novel attachment.

It will be apparent to those skilled in the art to which my invention appertains that the device is susceptible to wide modification and change; hence it will be understood the invention is not to be confined literally to the exact details as set forth only in so far as they are circumscribed within the scope of the appended claims.

What I claim as new and desire to secure by Letters Patent is:

1. In combination with a printing press, an independent fountain connected to said printing press, and horizontally and vertically adjustable relatively thereto, a plurality of rollers in said fountain, one of said rollers being engaged by the ink transmitting rollers of said printing press, one of the other of said rollers being mounted for horizontal and vertical adjustment relatively to said last mentioned rollers.

2. In combination with a printing press having a frame, a platen and ink reciprocating rollers; an independent fountain detachably connected to said frame of said printing press, said fountain having a plurality of rollers actuated independently from a separate source of power than that of the printing press, one of the rollers of said fountain being intermittently engaged by the printing rollers of said printing press, and means to adjust horizontally and vertically the fountain and consequently the rollers relatively to the frame of said printing press.

3. In combination with a printing press, a fountain detachably connected thereto, a plurality of rollers in said fountain, one of said rollers being mounted for horizontal and vertical adjustment relatively to the other of said

rollers, a plurality of inking rollers reciprocating over a printing surface and engaging intermittently one of the inking rollers of the fountain, a rockingly mounted platen on the frame of the printing press, said platen and the material therein engaging the printing surface of said printing press when the printing rollers of the printing press have been reciprocated to an upward position.

10 4. A printing press comprising a rockingly mounted platen, reciprocating inking rollers traveling over a printing surface and ink distributing means, a fountain slidably and adjustably connected to the frame of said printing press, having a plurality of inking rollers actuated from a source of power independent of the power operation of said printing press, the inking rollers of said printing press engaging the inking rollers of said fountain intermittently, whereby ink and colors are distributed from the rollers of the fountain to the printing surface of the printing press.

15 5. A printing press comprising a frame providing a rocking mount for a platen, inking rollers resiliently connected to an oscillating arm, said inking rollers traveling over an inking surface, and an ink distributing plate to an ink distributing roller operatively connected to a plurality of other rollers within said fountain, and means to rotate the rollers in the fountain independently of the operation of the mechanism for operating the printing press.

20 35 6. A separate attachment for a printing press consisting of a water color containing fountain, a plurality of rollers revolvably mounted on said fountain, one of said rollers being provided with means for vertical and horizontal adjustment thereof, relatively to the other said rollers, means to adjustably support said attachment to a conventional printing press, said printing press having means to distribute water colors from said fountain on to a printing surface which is engaged periodically by a platen rockingly mounted on the frame of said printing press.

25 40 45 7. A printing press comprising a frame, a rockingly mounted platen on said frame, a plurality of oscillating inking rollers also mounted on the said frame, said inking rollers traveling over a printing surface, and a distributing plate to a fountain having a plurality of rollers mounted thereon, means to rotate at variable speeds the rollers within said fountain, means to adjust one of the rollers in the inking fountain relatively to one of the other rollers, said last mentioned adjusting means consisting of a bearing journal having a resiliently mounted block supporting the said adjustably mounted roller in said fountain, and means to raise and lower the block relatively to the journal.

50 55 60 65 8. A printing press comprising a frame

having a platen and inking rollers, a fountain adjustably secured to said frame, said fountain having a plurality of rotatably mounted rollers actuated by a source of power independent from the said printing press, means to adjust one of said rollers relatively to another, means to remove excess ink from the said another roller, said last mentioned roller being engaged by the inking rollers of said printing press on their upward reciprocation.

70 75 80 85 90 95 100 105 110 115 120 123 129

9. A printing press comprising a base, a frame secured to said base, a platen and a plurality of inking rollers mounted for oscillation on said frame, a detachably mounted fountain adjustably secured to said frame, a plurality of rollers revolvably mounted on said fountain, said rollers being revolved independently of the platen and of the inking rollers of the printing press, means to adjust one of the rollers in the fountain relatively to another of the rollers therein, means to remove excess ink and color from the said another of the rollers and means to transfer ink from the fountain by means of the inking rollers of the printing press to a printing surface thereon to be engaged by material in the platen.

In testimony whereof I have signed my name to this specification.

CLYDE DEAN. 95
